SLIDING ABUTMENT TYPE ROTARY
INTERNAL-COMBUSTION ENGINE

Friedrich Kunz, Lucerne, Switzerland

Application August 7, 1947, Serial No. 767,263
In Switzerland March 30, 1943Section 1, Public Law 690, August 8, 1946
Patent expires March 30, 1963

9 Claims. (Cl. 123—14)

1

The present invention relates to motive means and more particularly to a fluid actuated motor in which a propelling force is developed by rotors and transmitted to a motor shaft.

It is an object of this invention to provide a fluid actuated motor rendering it possible to reduce to a minimum the losses due to friction.

It is another object of the present invention to provide means permitting a substantial decrease in the wear and tear of components heretofore encountered in rotary type motors.

It is a further object of the present invention to provide rotary means rendering it possible to obtain greater power than can be obtained from a comparable piston type motor.

It is a still further object of the present invention to provide rotary means of the aforesaid type which runs smoother and without substantial vibration.

Briefly described, the present invention relates to a motor including rotors attached to a machine shaft and rotated within a casing. The rotors or wheel bodies are provided at their respective circumferences with at least one compartment rotating with the rotor. The compartment is formed by a cavity bounded by at least one cross wall fitted with a sealing set of packing strips. The casing is provided with at least one slide valve which periodically projects into the rotary compartment and also periodically clears the interior or rotary compartment thereby facilitating the passage of the bounding cross wall.

In addition to the aforesaid slide valve, there is provided an admission opening for the driving medium and an outlet opening arranged so that a power expansion or working pressure chamber is formed in the rotary compartment between one side of the cross wall of the rotary compartment and one side of the slide valve and an exhaust chamber between another side of the cross wall and the rotary compartment and another side of the slide valve.

In the motor constructed according to the present invention the driving medium does not act on a conventional reciprocable piston but acts within a rotary compartment of a rotor or wheel body rotating in a casing into which is periodically projected a slide valve. The pressure acts in these rotary compartments thus setting the wheel body into rotary movement and effecting the transmission of a propelling force directly to the shaft of the motor.

With this type of motor it is possible to reduce to a minimum the friction resistance and other losses through wear and tear normally encoun-

2

tered in heretofore known rotary motors. The running of the present motor is much smoother, more uniform and substantially without vibration since very little noise is produced because the outlet of the consumed driving medium takes place under a relatively weak pressure.

For a motor of a particular output it is possible, according to the present invention, to reduce the size of the motor and the quantity of the required driving medium in comparison to heretofore known rotary motors.

The motor of the present invention may be driven by steam, compressed air and all other solid or liquid fuels or gases. Referring particularly to combustion fuels, such as gasoline, paraffin, crude oil and gas, the present motor provides for this type of fuel one or more compression devices that can be designed according to the piston system or as rotary machines.

The above description and objects of the present invention will be best understood by reference to the specification in conjunction with the drawings, wherein:

Fig. 1 is a vertical section of the present rotary motor taken across the shaft of the machine on section line 1—1 of Fig. 3;

Fig. 2 is a vertical section of the present motor taken across the shaft thereof on section line 2—2 of Fig. 3;

Fig. 3 is a vertical section taken parallel to the shaft of the motor on section line 3—3 of Fig. 1;

Fig. 4 is a plan view, with parts broken away, and shown in section on line 4—4 of Fig. 3;

Fig. 5 is a side elevational view taken from the right of Fig. 2, with parts broken away, and shown in section;

Fig. 6 is an enlarged cross sectional view of a compartment of one of the rotors with a slide valve projecting therein.

Referring with particularity to the drawings, 40 there is shown the machine or motor of the present invention which includes a casing 1 in which is housed a central shaft 3, the latter passing through the side walls 2 of the casing 1. Mounted on the central shaft 3 are two wheel bodies or rotors 4 and 5 which are arranged in spaced parallel relation with respect to each other and are rotatable with the shaft 3 within the wheel casing 1.

The wheel bodies or rotors 4, 5 are each provided at their peripheries with four similar rotary compartments 6 formed by a depression in the periphery of the wheel body or rotor. The depression, as illustrated in Fig. 6, is semi-circular in cross section and is provided with cross walls 7 at spaced intervals thereabout which di-

vide the depression or cavity into the aforesaid rotary compartments.

It is apparent to one skilled in the art that the cross section of the respective rotary compartments can be of any other suitable form, but the one illustrated facilitates a good sealing thereof. The cross walls 7 of the rotor 4 are displaced at an angle of approximately 45° with respective other cross walls of the rotor 5.

The cross walls 7 of the respective rotors 4, 5 are fitted at their free borders with sets of packing strips 8 and further with a strip 9 for lubricating oil, the latter acting as a scraper gliding along on the inside of a running surface 10 provided in the casing 1.

The lubrication and scraper strips 9 protrude sideways into the lubricating channels 11 disposed laterally in the wheel casing 1. Each rotary compartment 6 of the respective rotors is tightened up on both sides by several packing strips 12 which are placed next to each other, the innermost one of the packing strips 12 extending toward the neighboring rotary compartment, as clearly illustrated in Fig. 6.

In order to maintain the sides of the rotary compartment tight, a similar structure may be employed and instead of using strips on the sides of the rotary compartments packing strips may be fitted to the casing opposite the side walls of the rotary compartments. Further strips may be provided on the casing as well as on the side walls of the rotary compartments.

Mounted within the casing 1 are the slide valves 13, 14 each of which is periodically projectable into the rotary compartment situated therebelow. The slide valves 13, 14 are each surrounded by a jacket 15 containing a suitable cooling medium. It is apparent that the cooling may also take place in the slide valves.

As clearly illustrated in Fig. 6, the slide valves 13 and 14 are provided with different sealing bars 16 to keep the respective valves tight, said bars being U-shaped and extending toward the rotary compartment. Suitable pressure elements 17 are provided to keep the sealing bar 16 tight against the casing 1. When a cross wall 7 passes the slide valve, the latter is synchronizingly pushed to a position exteriorly of the rotary compartment. Due to the fact that the packing strips 8 hug the side wall of the housing when the cross wall of the respective rotary compartment passes the slide valve, a perfect sealing and safe passage of the respective cross walls of the rotary compartments are assured. Instead of reciprocable slide valves, it is possible to use valves of the rotary type.

As shown in Figs. 1, 2, 4 and 5, the slide valve 13 is operated by the levers 17 and 19 on shaft 18, tappets 20, and lever 22 on the axle 21. The lever 22 carries a stud 25 placed within a guide channel 23 of cam wheel 24 and a hook 26 engaging the guiding ridge 27 of the aforesaid cam wheel. The lever 22 is biased by means of a spring 28 to effect a prompt closing action.

As clearly illustrated in Fig. 5 the cam wheel 24 is keyed to the shaft 29 and is mounted thereon to be laterally displaceable. When the cam wheel 24 is set in motion, it operates various controls through the gear 30 which is situated within the rotor 4 together with the gear 31 which is opposite the central shaft 3.

The lateral displacement of the cam wheel 24 is effected by means of the guide channel 32 (Fig. 6) provided in the rotor 5 being engaged by the stud 33 (Fig. 5) of the rod 34, the latter being secured to the cam wheel 24 by means of the

ring 35. The guide channel 32 cams the stud 33 so that after each revolution of the cam wheel 24, the latter is axially displaced in one direction or the other.

Through the lateral displacement of the steering cam a sequential operation is obtained in which, during alternate revolutions, the stud 25 runs in the guide channel 23. The arrangement of the rise and dwell portions of the guide channel or cam tracks 23 (Fig. 2) causes the slide valve 13 to be opened, the valve being closed again immediately and quickly after the passage of the cross wall of the rotary compartment due to the biasing effect of the spring 28.

A space is provided in the inside of guiding ridge 27 for the hook 26, the bottom of this space running parallel to guide channel or cam tracks 23, as shown by the dotted lines in Fig. 2. The cam wheel 24 is provided on its other side with a channel guiding ridge 36 and guide channel 37 whereby in the particular position of the cam wheel, illustrated in Fig. 5, the stud 38 lies exteriorly of the guide channel 37 and the slide valve 14, normally actuated by the guiding ridge 36 cooperating with the hook 39 on the lever 40 carried on axle 21, tappet 42, and levers 41 and 44 carried on shaft 43, is maintained in a closed position.

After the lateral displacement of the cam wheel 24 the stud 38 engagingly glides into the channel 37 and, in the same manner as previously described, slide valve 14 is operated by the lever 40, the tappet 42 and levers 41, 44. The final closed gage of the slide valves 13 and 14 is obtained by means of the adjustment screws 45 (Figs. 1 and 5) on which the levers 19 and 41 are mounted. The tappets 20 and 42 are installed so that they can be timed at will whereby an accurate and safe opening and closing of the slide valves are assured.

By means of the gear 30 within the rotor 4, the crank shaft 47 is set in motion together with movable gears leading to shaft 3 by means of a gear 46, shown in dotted lines in Figs. 1 and 3. The central shaft 3 is connected to the rod 48 and the compression piston 49 which is reciprocable in the cylindrical casing 50, the latter being mounted between the two rotors 4, 5. The cylindrical casing is surrounded by a cavity 51 which is adapted to contain a cooling medium. A suction channel 51' is provided in the cylindrical casing 50 for the admission of air into the latter.

Mounted transversely of the suction channel is a valve 52 which is actuated by the cam wheel 24 by means of the tilting lever 54 which is pivoted on the axle 53. Accordingly in response to the movement of the cam wheel 24 the valve 52 permits the intake of the fuel by suction. The tilting lever 54 is biased onto the cam wheel 24 by means of the valve spring 55, the lever 54 carrying a cam engaging roller 56 which runs along a peripheral cam track 57 provided on the cam wheel 24.

In lieu of the compression piston illustrated it is apparent that rotary compressors may be employed.

Two channels 58 and 59 (Fig. 3) are provided in communication with the cylindrical casing 50, the channels passing through the motor casing 1. Mounted within the channels 58, 59 are the admission valves 60, 61. Two expansion or combustion chambers 62 and 63 are formed and through enlarged cavities are brought into communication with the rotary compartment in the vicinity of the admission valves 60 and 61.

Mounted within the combustion chambers are the spark plugs 64 and 65 (Fig. 4). Instead of spark plugs it is apparent that an injection system for the fuel may be used.

The admission valves 60 and 61 are actuated by the levers 68 and 69 mounted on the axle 66, the levers resting each on a respective cam track or surfaces 70 and 71 and being provided with rollers running along the cam tracks.

The cam tracks or surfaces 70, 71 are raised only on one-half of their respective circumferences and therefore the lateral displacement of the cam wheel 24 takes place so that during each revolution of the same one valve is maintained in a closed position while the other admission valve is brought into action.

Accordingly the admission valves 60 and 61 are operative alternately under the action of the cam wheel. The openings 74 are provided to expel the consumed driving medium.

As illustrated in Figs. 1 to 3, inclusive, there is provided an oil reservoir 72 in which an oil pump, not shown, is mounted. The lubrication of the shaft 3 takes place through oil pipes (not shown) connected to the aforesaid pump. Further a special oil pipe (not shown) communicates with each cross wall 7 of the rotary compartment 6 and to the lubrication scraper 9. The special oil pipe further leads to a lateral lubrication oil channel 11 and from the latter the lubricating oil is conducted back again to the oil reservoir 72.

The aforesaid system facilitates the lubrication of all of the sliding surfaces in the casing during revolution of the rollers. Other oil pipes lead to the slide valves 13 and 14 from the oil pump, these pipes terminating on both sides near the U-shaped packing strips 16 of the slide valves and accordingly the sliding surfaces between the slide valves and the rotary compartment are also lubricated. When the slide valves are opened during operation, the oil feed for the respective valves is suspended. By the aforesaid lubrication system, the crank shaft, the compressor, the bearings, and the entire control mechanism are suitably lubricated.

Through the covering 73 all the slide valves and control mechanisms are suitably protected. The actuation of the ignition means 64, 65 is effected from the cam wheel 24 in a manner which will be clear and, therefore, has not been illustrated. The expansion combustion chambers 62 and 63 are surrounded by suitable cavities 75 adapted to contain a cooling medium.

However, instead of these cavities finned tubular radiators for air cooling may be employed. The aforesaid motor having the rotary compartments is operated with gasoline as the fuel, as will now be described.

The position of the motor illustrated in Fig. 1 is the position immediately after the beginning of the combustion process. The rotors 4 and 5 are moving in the direction of the arrow in Fig. 1. The suction valve 52 is opened by the cam wheel 24 acting through the cam track 57.

The suction of the fuel from the carburetor, not shown, then takes place in response to the down stroke of the compressor piston 49. When the down stroke for the intake of fuel is terminated, the suction valve 52 is closed and the fuel is subsequently compressed to about one atmosphere through the compression stroke of the piston in the cylindrical casing 59. In the meantime the slide valve 13 has been pushed also permitting the passage of the cross walls 7 of the rotor released by slide valve 13.

The slide valve 14 is opened in a manner similar to the opening of the slide valve 13, the latter being actuated as follows:

The lever 22 is lifted up by the stud 25, and this movement is transmitted to the slide valve 13 by means of the tappet 20, the lever 19, the shaft 18 and lever 67. The spring 28 which rests on the lever 22 is compressed and immediately after the passage of the cross wall 7 of the rotor contiguous to the slide valve 13, the slide valve is closed quickly due to the sharp bend in the guide channel 23.

Immediately after the closing of the slide valve 13 the admission valve 60 is opened by action of the raised portion of the cam track 70 of the cam wheel 24, the motion being transmitted over the lever 68. By the same stroke, the fuel which is beforehand compressed to about one atmosphere in the compressor is compressed to approximately six atmospheres through the channel 58 in the combustion chamber 62. At the moment when the compression stroke is terminated the admission valve 60 is closed and the fuel mixture is brought to combustion, as previously described. Due to the pressure resulting from the explosion of the fuel mixture in the combustion chamber 62 the cross wall 7 of the rotary compartment is pushed away from the slide valve 13 and rotated in the direction of the arrow and thus the motor shaft is likewise rotated.

The burnt gas is conducted through the rotary compartment and through the casing until the first cross wall of the rotor has passed the slide valve and the slide valve is again closed, whereupon the burnt gas is expelled through the opening 74. During the combustion and also immediately after the closing of the valve 13 the cam wheel 24 is laterally displaced so that the stud 25, during the next revolution of the cam wheel, is exteriorly of the guide channel 23 by virtue of the cooperation of the stud 33 with the rod 34.

Then, during revolution of the cam wheel, the slide valve 13 is maintained in the closed position by the guiding ridge 27 together with the hook 26, engaging in it, over the actuating mechanism. The lateral displacement of the cam wheel 24 simultaneously results in the maintenance of the admission valve 60 in a closed position during the revolution of the cam wheel, due to the fact that the roller of the tilting lever 68 runs outside of the cam track 70.

Directly after the closing of the admission valve 60, the suction valve 62 is again opened and the action of suction and compression is repeated, but this time in such a manner that the compressed fuel is fed into the combustion chamber 63 through the admission valve 61. The function of the valve and slides actuated by the lateral displacement of the cam wheel 24 is the same as previously described and force is again transmitted from the combustion chamber 63 to the shaft 3.

While there is still an expansion in the compartment of one of the rotors another combustion takes place in the other rotor and thereby the machine shaft 3 is always subjected to a propulsion force. With reference to the motor having the rotary compartments, as described in the drawings, there occurs eight combustions in the two rotors for every revolution of the machine shaft.

A special advantage is derived from the fact that the size and general construction of the present motor may be adapted at will for various purposes and required uses.

When it is desired to use as a driving medium, steam, compressed air or similar non-combustibles, the construction of the motor will be on the same principle but without the compressor.

It can thus be seen that there has been provided in accordance with this invention, in combination, a motor, a casing, a shaft rotatably journaled in said casing, rotor means fixedly secured to said shaft, said rotor means being provided with at least two axially spaced rotary compartments, first control means for admitting a motive fluid to one of said compartments, thereby imparting a torque to said shaft, and subsequently discharging said motive fluid therefrom, second control means for admitting a motive fluid to the other of said compartments, thereby imparting a similar torque to said shaft, and subsequently discharging said motive fluid therefrom, and operating mechanism for alternately actuating said first and second control means, said operating mechanism comprising a cam wheel, mounting means rotatably securing said cam wheel to said casing in axially displaceable manner, transmission means coupling said cam wheel with said shaft for synchronous rotation, and linkage means engaging said cam wheel and controlled by said rotor means for placing said cam wheel in a first axial position during a certain and in a second axial position during other revolutions of said cam wheel, said first control means including first cam follower means positioned to be displaced by said cam wheel in said first axial position only, said second control means including second cam follower means positioned to be displaced by said cam wheel in said second axial position only.

I claim:

1. In a motor, in combination, a casing, a shaft rotatably journaled in said casing, rotor means fixedly secured to said shaft, said rotor means being provided with at least two axially spaced rotary compartments, first control means for admitting a motive fluid to one of said compartments, thereby imparting a torque to said shaft, and subsequently discharging said motive fluid therefrom, second control means for admitting a motive fluid to the other of said compartments, thereby imparting a similar torque to said shaft, and subsequently discharging said motive fluid therefrom, and operating mechanism for alternately actuating said first and second control means, said operating mechanism comprising a cam wheel, mounting means rotatably securing said cam wheel to said casing in axially displaceable manner, transmission means coupling said cam wheel with said shaft for synchronous rotation, and linkage means engaging said cam wheel and controlled by said rotor means for placing said cam wheel in a first axial position during certain and in a second axial position during other revolutions of said cam wheel, said first control means including first cam follower means positioned to be displaced by said cam wheel in said first axial position only, said second control means including second cam follower means positioned to be displaced by said cam wheel in said second axial position only.

2. In a motor the combination according to claim 1, wherein said rotor means comprises a pair of axially spaced wheel-bodies, said cam wheel being disposed intermediate said wheel-bodies and parallel thereto.

3. In a motor the combination according to claim 1, wherein one of said wheel-bodies is provided with a guide channel facing said shaft, said

linkage means comprising an arm provided with a stud in engagement with said guide channel.

4. In a motor, in combination, a casing, a shaft rotatably journaled in said casing, rotor means fixedly secured to said shaft, said rotor means being provided with two axially spaced peripheral grooves and with cross walls partitioning said grooves, thereby forming said grooves into rotary compartments, a common source of motive fluid, 10 a first and a second slide each held displaceably in said casing adjacent a respective one of said grooves, fluid inlet and outlet means on opposite sides of said slides, a first pair of levers for respectively displacing said slides into and out of the respective grooves, valve means connecting said inlet means with said source of motive fluid, a second pair of levers for selectively operating said valve means to admit fluid from said source to a respective one of said grooves, and operating 20 mechanism for actuating said levers to operate each of said slides to enter the respective groove immediately after passage of a cross wall thereof past said slide, to admit motive fluid immediately thereafter into the space created between said cross wall and said slide, whereby a torque is imparted to said shaft, and to withdraw said slide upon approach of the next succeeding cross wall, the relative positions of said slides and of said cross walls being such that said slides alternately 30 register with respective cross walls during rotation of said shaft, said operating mechanism comprising a cam wheel, mounting means rotatably securing said cam wheel to said casing in axially displaceable manner, transmission means coupling said cam wheel with said shaft for rotation of said cam wheel at an angular velocity N times the angular velocity of said rotor means, N being the total number of compartments formed in both of said grooves, linkage means engaging said cam 40 wheel and controlled by said rotor means for placing said cam wheel in a first axial position during odd-numbered and in a second axial position during even-numbered revolutions of said cam wheel, and first and second pairs of cam followers for operating said first and second pair of levers, respectively, from said cam wheel, one cam follower of each of said pairs being positioned to be displaced by said cam wheel in said 45 first axial position only, the other cam follower of each of said pairs being positioned to be displaced by said cam wheel in said second axial position only.

5. In a motor the combination according to claim 4, wherein said cam wheel is provided with a pair of raised surfaces extending partly around the circumference of said cam wheel, each of said raised surfaces being of such width as to be engageable by a respective cam follower of one of said pairs in a respective one of said axial positions only.

6. In a motor the combination according to claim 4, wherein said cam wheel is provided on each of its two faces with a respective guide channel, the cam followers of one of said pairs comprising a pair of studs positioned adjacent said two faces, respectively, and adapted to enter a respective one of said guide channels in a respective one of said axial positions only.

7. In a motor the combination according to claim 6, wherein each of said two faces of said cam wheel is provided with a respective circular ridge, each of said studs being provided with a respective extension engaging said circular ridge in that axial position of said cam wheel in which

the respective stud does not engage the respective guide channel.

8. In a motor the combination according to claim 7, wherein each of said extensions is in the form of a hook, each of said ridges being undercut to provide a clearance for said hook in that axial position of said cam wheel in which the respective stud is engaged by the respective guide channel.

9. In a motor the combination according to claim 4, wherein said source of motive fluid includes a piston cylinder provided with a suction valve, a piston in said cylinder and an additional cam follower for operating said suction valve, said cam wheel comprising a control surface cooperating with said additional cam follower in each axial position of said cam wheel, said piston being synchronized with said cam wheel by way of said transmission means.
